H. LEWIS

SPOUT FOR DISPENSING RECEPTACLES

Filed Sept. 17, 1923

Inventor
Harvey Lewis
by George Crammer Atty.

UNITED STATES PATENT OFFICE.

HARVEY LEWIS, OF CHICAGO, ILLINOIS.

SPOUT FOR DISPENSING RECEPTACLES.

Application filed September 17, 1923. Serial No. 663,060.

To all whom it may concern:

Be it known that I, HARVEY LEWIS, a citizen of the United States, residing at Chicago, in the county of Cook and State of Illinois, have invented new and useful Improvements in Spouts for Dispensing Receptacles, of which the following is a specification.

This invention relates to spouts for liquid dispensing receptacles, such as are used at garages and gasoline filling stations for conveniently supplying crank cases of motor vehicles with measured quantities of oil.

The principal object of my invention is to vent the container directly through the spout while discharging liquid therefrom by providing in the spout means restricting the flow of liquid to the spout from the container to less than could be accommodated by the discharge end of the spout, so that the spout not completely filled with liquid allows air to freely enter the same through the discharge end for venting the container.

Another important object of my invention is to so construct such means that the outflow of liquid from the spout will be automatically controlled by turning the spout about its longitudinal axis while the spout is in inclined pouring position. This allows the flow of oil from the spout while being poured into the receiving pipe of an engine crank case to be checked or reduced without removing the spout from said pipe whenever the oil tends to overflow or choke by backing up therein.

The invention consists further in the structural and other matters hereinafter described and more particularly set forth in the appended claims.

40 In the accompanying drawings—

Fig. 1 is a perspective view of an oil dispensing container with a spout of my invention;

Fig. 2 is a longitudinal sectional view of the spout and attached cap removed from the container;

Fig. 3 is a view looking into the cap at the inner end of the spout; and

Fig. 4 is a vertical sectional view taken on the line 4—4 of Fig. 2.

The spout of my invention comprises an outside tubular body member 1 preferably made of metal and tapering from its base to its outer end where it is cut off on an angle as shown. At the base of the spout 1 is a

closure cap 2, by means of which the spout may be applied to a container 3, which may be metal, glass, or any other material. In the particular form of structure shown, the cap 2 is made integral, by soldering or otherwise, with the spout 1 so that the two form a one-piece or unitary structure, although a two-part structure may be employed, if desired, for placing the spout inverted in the container 3 for shipment and storage. In 60 the structure shown, the cap 2 is threaded so that it may be screwed on the upper threaded end of the container 3.

Located in the spout 1 is a short tube section 4. This has a diameter less than the 70 inside diameter of the spout 1 at its discharge or outer end and is eccentrically arranged with respect to the center line thereof, as shown in Figs. 3 and 4. By this arrangement, a passageway 5 is provided between the tube 4 and the spout 1. The tube 4 extends into the spout about one-third of the latter's length and thus has its outer end terminating short of the outer end of the spout 1. The inner end of said tube 4 extends into the cap 2 beyond the base of the spout, as shown in Fig. 2. About the tube 4 at or adjacent the base of the spout 1 is provided a partition wall 6, which closes the passageway 5 to the cap 2 except through 75 a small opening or aperture 7 provided in said partition wall. The inner end of the inner tube 4 extends through the partition wall 6 beyond the aperture 7 and is there cut off at an angle toward the base of the 80 spout 1, as shown in Fig. 2.

The tube 4 provides the only outlet to the spout 1 from the container 3 and this outlet, having a diameter or area less than that at the discharge end of the spout, does not 95 permit as much liquid to enter the spout from the container 3 as the discharge end of the spout will accommodate. The spout not being completely filled with liquid while flowing through the same allows air to 100 freely enter the spout through its outlet or discharge end and vent the container 3 through the passage 5 and aperture 7. The container 3 is thus vented directly through the spout itself during the discharging operation without the use of separate vent tubes, as heretofore. This cheapens the construction of the device and makes it simple in operation. The inner end of the tube 4 extending into the cap beyond the air hole 105 110

7 provides a baffle for the latter and not only prevents the liquid being discharged from the container from entering the aperture 7 to close it, but also prevents the air 5 vented into the container from short-circuiting and passing out with the liquid through the tube 4, when the container 3 is held in inclined pouring position, that is, at an angle to the vertical, with the hole 7 uppermost.

Baffling the air in this manner allows for automatically controlling the outflow of liquid from the container whenever desired, as by oscillating or turning the container 15 around its longitudinal axis to bring the vent hole 7 on the lower side of the baffle. When brought to this position, the air currents rushing into the container through the hole 7 from the air passage 5 meet above the 20 baffle and, entering the tube 4, check or reduce the outflow of liquid from the container. This allows the discharge of oil from the spout 1 into a receiving pipe of an engine crank case to be controlled whenever desired to prevent overflow of said pipe 25 in the manner heretofore stated. Thus around garages and filling stations a waste of oil is prevented by not overflowing these pipes while pouring into them, as heretofore.

Turning the container in the manner stated to bring the vent opening 7 to its lowermost position, the outflow of liquid from the spout 1 will result in reducing the 35 outflow of liquid from the spout 1 to approximately one-third of its normal flow. In other words, it will take approximately three times longer than when in normal flowing position, that is with the opening 7 40 uppermost. Practice has fully demonstrated this and has also shown that with a quart size container, equipped with my spout, the container will empty in approximately seven seconds when held in normal discharging 45 position, while it will require about eighteen seconds to empty when in checked or retarded position.

The spout 1 being carried by the cap 2 makes the two in effect the entire spout. 50 With the inner or baffle end of the tube 4 projecting into the cap, the tube is within the confines of the spout. The spout 1 is preferably straight, and is applied to the cap in a manner to extend coaxially from the container 3 when the spout is on the container.

The outer end of the spout 1 is cut off at an angle to indicate the low side of the spout while emptying the container 3. The air 60 vent 7 is arranged on the high side of this cut off so that when the spout is held down for pouring the aperture 7 is up and will not fill with liquid to interfere with its venting function. The inner end of the tube 4 is also cut off on a bevel to allow for com-

plete draining of the receptacle when inverted. The cap 2 is made dome shaped for this same purpose.

The spout 1 is adapted for any dispensing receptacles or containers from which liquid is discharged by a spout, and I do not wish to be limited to the application of my invention to oil dispensing containers as employed at garages and gasoline filling stations for supplying crank cases with oil. 75 While the spout 1 is tapered, the tube 4 may have a substantially uniform diameter.

While I have shown and described herein in detail a spout constructed in accordance with my invention, it is of course to be understood that the details of construction and arrangement of parts may be variously changed and modified without departing from the spirit and scope of my invention.

I claim as my invention:

1. The combination with a dispensing receptacle, of a spout attached thereto, means in the spout dividing the same into an air vent passage and a liquid outflow passage, the latter being smaller than the discharge 90 end of the spout, and partition means extending across said air passage and having a vent opening therefor.

2. The combination with a dispensing receptacle, of a spout attached thereto, a tube 95 in said spout and smaller than the same to provide an air vent passage between the tube and the spout, and a partition wall extending across said passage and having a vent opening therefor, said tube opening 100 through said wall for the outflow of liquid from the container to the spout.

3. The combination with a dispensing receptacle, of a spout attached thereto, a tube in said spout and arranged eccentric thereto 105 to provide an air vent passage between the tube and the spout, and a partition wall extending across said passage and having a vent opening therefor, said tube opening 110 through said wall for the outflow of liquid from the container to the spout.

4. The combination with a dispensing receptacle, of a spout attached thereto, a tube in said spout and smaller than the same to provide an air vent passage between the 115 tube and the spout, and a partition wall extending across said passage and having a vent opening therefor, said tube extending through said wall for the outflow of liquid from the container to the spout, said tube 120 having its inner end extending beyond said wall to provide a baffle for said vent opening and beveled off from its extreme inner end toward said partition wall.

5. An article of manufacture, comprising 125 a tapered dispensing spout, a tube of substantially uniform diameter in said spout and having a diameter less than that of the spout to provide an air passage between the same, said tube arranged eccentric in said 130

spout and being adjacent the inner end of the same, and a partition wall at the base of the spout closing the passage between the spout and tube, said partition wall having a vent opening.

6. The combination with a dispensing receptacle, of a spout attached thereto, and means within the spout for automatically controlling the outflow of liquid therefrom upon turning the container about its longitudinal axis when the container is held in an inclined pouring position.

7. The combination with a dispensing receptacle, of a spout attached thereto, and means within the spout for automatically controlling the outflow of liquid therefrom upon turning the container about its longitudinal axis when the container is held in an inclined pouring position, said means 20 acting on a half turn of the container to check the flow of liquid therefrom to approximately one-third of its normal flow.

8. The combination with a dispensing receptacle, of a spout attached thereto, and

means including a baffle and a vent opening 25 within the spout for automatically controlling the outflow of liquid therefrom upon turning the container about its longitudinal axis when the container is held in an inclined pouring position.

9. The combination with a dispensing receptacle, of a tubular spout attached to said receptacle and extending straight outward from one end thereof, and means dividing the spout into an air vent passage and a 35 liquid outflow passage with the latter smaller than the former, said means including a baffle and a vent opening for automatically controlling the outflow of liquid from the receptacle into said liquid outflow passage 40 upon turning the container about its longitudinal axis when held in an inclined pouring position.

In testimony that I claim the foregoing as my invention, I affix my signature this 45 15th day of September, 1923.

HARVEY LEWIS.
